UNITED STATES PATENT OFFICE.

CALEB E. BROWN, OF JACKSON, MICHIGAN.

HOOP-SKIRT.

SPECIFICATION forming part of Letters Patent No. 329,271, dated October 27, 1885.

Application filed June 23, 1885. Serial No. 169,493. (No model.)

To all whom it may concern:

Be it known that I, CALEB E. BROWN, a citizen of the United States, residing at Jackson, in the county of Jackson and State of Michigan, have invented certain new and useful Improvements in Hoop-Skirts, of which the following is a specification.

My invention relates to an improved hoop-skirt; and it consists of certain features of construction and arrangement of parts, hereinafter fully set forth, and designated in the claim.

In the drawings herewith, which illustrate the invention, Figure 1 is a front perspective view of the hoop-skirt. Fig. 2 is a side perspective view.

The letter A designates the waistband; B, the two vertical front tapes; B', the two side tapes, and B² the rear tape, all of which hang from the waistband.

By preference all the hoops are made of a single continuous piece of wire. The commencing end of the wire may be located at any point. Commencing at a point, 1, at the side and near the front above where the knees would come, the wire passes up and diagonally across the front *e*, around one hip, *c*, across the back *d*, just below the waistband, around the other hip, *c'*, then inclining down and diagonally across the front *e*, where it crosses at *f* the first diagonal, then continuing down to the opposite side, *g*, then straight around the back *h* and up the side *i*, again up and diagonally across the front *c*, (below where it crossed first,) around one hip, *c'*, across the back *d*, around the other hip, *c''*, then again down and diagonally across the front, as before. These windings are repeated as often as may be deemed desirable—say from four to ten times. Each time the wire crosses one of the tapes it is made fast thereto by a suitable fastening or clip, *j*. By this construction these windings, which in the present instance number seven, form an upper nest or series of hoops, which have position at the top or back of the skirt, inclining therefrom as they cross the position of the hips and thighs, and leave below the front crossing-place, *f*, an inverted-V-shape space, *k*, for the knees.

Above the front crossing-point is the necessary front or abdomen opening, *U*, and the usual front buckle, *n*, of the waistband at

this point provides for spreading the skirt open when putting it on or adjusting it to the person.

An advantage of this construction in forming the front or abdomen opening, *l*, is that there are no ends of hoops attached to tapes, as is commonly the case in other skirts at each side of this front opening. Another advantage of this construction of the upper series of hoops lies in the absence of hoops at the seat. By reason of this seat opening or space *p* the wearer can take a seat without sitting on the hoops.

A lower nest or series of horizontal hoops, *L*, are suspended to the tapes, and the uppermost hoop of this series is low enough to avoid or remain below the knees of the wearer. The inverted-V-shaped knee space or opening above referred to is at the front between the uppermost hoop of the lower series and the front crossing-place, *f*, of the upper series. By preference the lower series of hoops are formed by a continuation of the same piece of wire which composes the upper series. The last hoop, *h'*, of the upper series merges into the lower series, and said wire terminates finally at the point 2. When the wearer sits down, the front crossed part, *f*, of the hoops will lie on the lap close up to the body, and the lower sides of the hoops in front will drop on the shins, while the knees of the person find room at the inverted-V-shape opening *k*.

Having described my invention, I claim and desire to secure by Letters Patent of the United States—

A hoop-skirt having in combination a waistband, vertical tapes hanging from the waistband, a lower series of horizontal hoops below the knee, and an upper series of hoops which extend across the back *d* just below the waistband, incline down at the hips, extend from the hips diagonally down and across the front, the portions which come from the opposite hips crossing each other in front, and each portion then extending to the opposite side and around the back *h*, as set forth.

In testimony whereof I affix my signature in presence of two witnesses.

CALEB E. BROWN.
